UNITED STATES PATENT OFFICE.

MAX SEIFFERT, OF LEIPZIG, GERMANY.

SEALING-CAP FOR BOTTLES.

SPECIFICATION forming part of Letters Patent No. 739,932, dated September 29, 1903.

Application filed April 29, 1903. Serial No. 154,792. (No model.)

To all whom it may concern:

Be it known that I, MAX SEIFFERT, a subject of the German Emperor, and a resident of Leipzig, Germany, have invented certain new and useful Improvements in Sealing-Caps for Bottles, of which the following is a specification.

This invention relates to a sealing cap or closure for bottles; and its object is to do away with the drawbacks usual to devices of the same kind and furnish a bottle-seal wholly free of germs. In most cases the closure or sealing of bottles is now accomplished by means of cork or india-rubber. Both materials, however, have the drawback that they cannot be exposed to the temperatures necessary for a complete and sure sterilization (300° Fahrenheit) without losing the qualities which render them suitable for attaining an inodorous or tasteless closure. At said temperature of 300° Fahrenheit both would be decomposed or dissolved, smell and taste of burning, and not be well applicable as a tight closure. Besides this the shape of such materials as used for sealing bottles in form of plugs, plates, or rings renders it necessary for them to be touched by hand for the purpose of closing the vessels. Thus a reinfection of such bodies is unavoidable even if they previously had been subjected to a mostly insufficient chemical disinfection.

My sealing cap or closure for bottles consists of tin-foil free of lead and of corresponding thickness which on its part opposing the bottle-opening is provided with an elastic relaxable cover. This cover is composed of caragheen or agar, which in a three per cent. to five per cent. watery solution, with one-half to one per cent. of chemically-pure glycerin, may be stiffened and dried. Thus leaves of tin-foil are produced which on one side are covered by elastic agar relaxable in condensing steam or water. These leaves are cut into strips and wound in rolls inclosed in a packing of paper. As tin melts at 446° Fahrenheit, glycerin only at 554° Fahrenheit, these rolls can be sterilized in dry heat of 300° Fahrenheit. For making use of such strips I prefer to perforate them at suitable distances in the form of a circle, so that the diameter of the circles corresponds to the nec-

essary breadth of the seal. In the annexed drawings such a sealing-cap is represented.

Figure 1 is a front or top view, Fig. 2 a longitudinal section, and Fig. 3 a cross-section, thereof.

1 is the elastic metal strip provided at 2 with a covering of relaxable elastic material. The thickness of this metal disk 1, which, as stated above, preferably is composed of tin-foil free of lead, naturally is very different in each case. It depends thereupon if duplicates are admissible on the seal, when the disk of tin-foil may be optionally thin or if the closure has to be accomplished in such a manner that in consequence of the elasticity of the material any duplicate has to be avoided and an equable removing or blocking of the material at the periphery of the circular disks 3 takes place. In the latter case the thickness of the disk of tin-foil applied should not surpass a fixed measure.

Having now fully described my invention, I declare that what I claim is—

1. An aseptic sealing-cap for bottles consisting of a metal disk provided with a relaxable elastic covering, substantially as set forth.

2. An aseptic sealing-cap for bottles consisting of a metal disk of tin-foil free of lead said disk being covered with a film consisting of three to five per cent. agar or caragheen and of one-half to one per cent. pure glycerin, substantially as set forth.

3. An aseptic sealing-cap for bottles consisting of a circular metal disk provided with a relaxable elastic covering, substantially as set forth.

4. A blank for forming aseptic sealing-caps for bottles, consisting of a metal strip provided with a relaxable elastic cover and containing perforations forming lines about portions of the blank, said portions corresponding in size to the caps to be formed therefrom, substantially as described.

In testimony whereof I affix my signature in presence of two witnesses.

MAX SEIFFERT.
